CLAIM

The ornamental design for a top sheet having lower section with quilted insert, as shown and described.

DESCRIPTION

FIG. 1 is a view in perspective of a top sheet having lower section with quilted insert;

FIG. 2 is a side elevational view of the top sheet having lower section with quilted insert;

FIG. 3 is a view in cross section taken along the arrowed lines 3 of FIG. 2; and,

FIG. 4 is a top plan view of FIG. 1.

The broken lines in FIGS. 1, 2, and 4 at the lower section of the top sheet are understood to represent quilt stitching, and form a part of the claimed design. The broken and dashed line showing of a mattress in FIGS. 1, 2, and 4 is for illustrative purposes only and forms no part of the claimed design.
